CLAIM

We claim the ornamental design for an oval promotional display, as shown and described.

DESCRIPTION

FIG. 1 shows a front perspective view of our design for an oval promotional display;

FIG. 2 shows a front view thereof;

FIG. 3 shows a rear view thereof;

FIG. 4 shows an enlarged top view thereof;

FIG. 5 shows a bottom view thereof;

FIG. 6 shows a side view thereof; and,

FIG. 7 shows an opposite side view thereof.

In the drawings, the broken lines represent environmental structure forming no part of the claimed design.
